UNITED STATES PATENT OFFICE

ALONZO C. GOULD, OF EVERETT, WASHINGTON

COMBINATION BED DAVENPORT

Application filed October 29, 1928. Serial No. 315,814.

This invention relates to improvements in davenports and the like, and has particular reference to devices of that character known as bed davenports; it being the principal object of the invention to provide a combination bed and davenport in which that portion normally serving as the seat is of extra width and may be drawn out from within the main frame to an extended position to provide a bed of full width.

It is a further object of the invention to provide a bed frame of rigid construction that is slidably contained in the main frame and easily adjustable into and from the latter, and which provides for the full width bed without the usual unfolding of hinged sections.

It is also an object of the invention to provide a davenport of the above character wherein ample space is provided within the back portion for the storage of bedding and cushions.

It is a still further object of the invention to provide a device as above stated, that will be attractive in appearance and relatively inexpensive to manufacture.

Other objects reside in the various details of construction and in the combination of parts and in their mode of operation, as is hereinafter described.

In accomplishing these and other objects, I have provided the improved details of construction, the preferred forms of which are illustrated in the accompanying drawings, wherein—

Figure 1 is an end view of a bed davenport constructed according to the present invention; a portion of the end frame being broken away for the purpose of better illustration.

Figure 2 is a similar view of the device with the seat portion extended to form a full width bed.

Figure 3 is a sectional detail illustrating the arrangement of the bed frame within the main frame of the davenport.

Referring more in detail to the drawings—

The davenport, as here illustrated, comprises the usual upholstered, wooden frame structure, having opposite end frames or sections 1 and a wooden back portion 2; the

frame being supported by short legs 3 mounted by casters 4.

Along the top of the back portion 2, is the usual top or head cushion 5 which curves upwardly and forwardly. A back cushion 7 extends the length of the frame and, at its opposite ends, is fixed rigidly to supporting brackets 8 which are pivotally attached, by bolts or the like 9, to the inside edges of the top rails of the end frames 1 so that this cushion may swing pivotally from the normal position, as shown in Figure 1, to the position as shown in Figure 2. When in its normal position, the upper edge of the back cushion fits against the forward edge of the head cushion and, when in its other position, the cushion extends substantially in a horizontal position providing an open compartment 10 just below the head cushion which is convenient for containing the seat cushions 70 which will be removed from the seat when the device is to be used as a bed.

Each of the end brackets 8 which support the back cushion, when viewed in the position as in Figure 1, comprises an arm 8^a which, at 75 its end, receives the pivot bolt 9, upwardly and downwardly extending arms 8^b and 8^c and a rearwardly directed arm 8. Slats or the like, 11, extend lengthwise of the cushion between the brackets for the support of cushioning springs 12 and angle iron bars 13 and 14 are extended between the ends of the arms 8^b and 8^d, respectively, and to these bars, the ends of arcuate ribs 15 are attached in close relation to form an enclosure between the 80 slats and ribs for containing bedding or the like, as is indicated at 16; access to this compartment being provided when the back cushion is in the position of Figure 2.

Contained within the lower portion of the 90 main frame, is a bed frame 20 of box-like form that is slidably supported at its ends on the base rails, or plates, 21 of the end frames 1. This bed frame is slidably adjustable forwardly or outwardly from the main frame, 95 from a position at which its forward wall 20^a is substantially even with the forward edge of the main frame to a position at some distance forwardly thereof so as to provide a bed bottom of full width. When the bed 100

frame is moved back to its inward limit, its rearward portion extends below and well back of the back cushion 7.

It is preferred to interpose rollers, as at 24, between the supporting rails 21 and the bottom rail of the bed frame and also to place similar guide rollers between the ends of the bed frame and the end portions 1 of the main frame, so as to insure easy movement, without binding, of the bed frame into and from the main frame. The bed frame is also provided, toward its outer edge, with legs 25 for supporting the forward part of the frame when it is in its extended position. These legs are also equipped with rollers, or casters, 26 to provide for easy adjustment. A mattress 30 is fitted within the bed frame 20 and this is preferably supported by the usual coiled springs 31 which are mounted on cross slats 32 supported by a plurality of flexible straps 33 attached, at their forward ends, to the bed frame and extended rearwardly and fixed to the cross bar 14 that extends between the arms 8^a of the pivoted brackets 8.

Assuming the device to be so constructed, it is apparent that when it is desired to use the davenport as a bed, the bed frame 20 may be drawn forwardly and this, through the connection of the straps 33 with the supporting brackets 8 for the back cushion 7, will cause the latter to swing rearwardly at its top edge, thereby opening up the compartment 10 below the head cushion within which the seat cushions 36 may be stored. It also gives access to the compartment beneath the back cushion in which the bedding is stored. A bed may then be made up on the mattress 30.

To close the device, it is only necessary to first remove the bedding from the mattress, 40 and this may, if desired, be placed in the compartment provided therefor. Then the bed frame is pushed back in the frame to its limit of travel. With inward movement of the bed frame, the cushion 7 swings upwardly 45 on its pivots to its normal position and in so swinging, it carries upwardly with it the inner edge of the mattress 30 and the supporting springs therefor, which assumes the upwardly curved position as shown in Fig. 1.

Having thus described my invention, what I claim as new therein and desire to secure by Letters-Patent, is:

1. In a combination bed davenport, a main frame structure, a back cushion frame structure disposed within the main frame to provide a downwardly opening compartment back of it, and having means at its ends by which it is pivotally mounted; pivotally mounted in the main frame to swing between normal closed position and horizontal open position, a bed frame having means by which it is slidably adjustable into and from the main frame below said back cushion frame, and a flexible bed bottom carried by the bed frame and attached along its inner edge to

said back cushion frame to be functionally supported thereby when the said frame is in open position and to be carried upwardly therewith into said compartment when the frame is swung from horizontal to normal position.

2. In a combination bed davenport, a main frame structure comprising opposite end sections, a back, a head cushion extending forwardly from the back, a back cushion having supporting brackets at its ends pivotally mounted in the end sections of the main frame so that the back cushion may swing between normal closed and horizontal open positions, a bed frame having means by which it is slidably adjustable forwardly from the main frame and a flexible bed bottom carried by the frame and attached along its inner edge to the back cushion frame, said back cushion frame being set forwardly within the main frame to provide a compartment back of it and said bed bottom being so attached to the back cushion that the inner edge will be carried upwardly into the compartment therewith when the cushion is swung from horizontal to normal position incident to inward adjustment of the bed frame.

Signed at Everett, Washington, this 25th day of August, 1928.
